UNITED STATES PATENT OFFICE

2,112,270

RESPIRATOR

Harvey S. Cover, South Bend, Ind.

Application April 27, 1934, Serial No. 722,619

4 Claims. (Cl. 128—146)

My invention relates broadly to respirators and has for an object the provision of such a device having a novel type exhaust valve and a novel construction of the respirator body for the purpose of attaching and securing the exhaust valve thereto. This invention is broadly related to my copending applications, Serial Nos. 662,929, 684,503, and 684,968, filed respectively on March 27, 1933, August 10, 1933, and August 14, 1933.

Another object is the provision of a respirator and means for protecting the exhaust valve from damage and also protecting it to a high degree from the entrance of foreign particles which might interfere with the proper working of the exhaust valve parts. It might be thought that the accomplishment of these objects would be accompanied by certain disadvantages such as inaccessibility, difficulty of removal, the necessity of a vision obstructing housing, et cetera; however, the exhaust valve retaining means of my respirator are placed in an accessible location, the exhaust valve may be easily removed for cleaning, adjustment, or replacement, and the protecting housing for the exhaust valve may be so positioned and arranged as not to interfere to any detrimental extent with the vision of the user.

Other objects of the invention are economy of manufacture, economy of replacement of parts, compactness, and efficiency.

Other objects will appear hereinafter.

My invention may be best understood by reference to the accompanying drawings, in which:

Fig. 1 is a top plan view of my device;

Fig. 2 is a side elevational view of the device; Fig. 3 is a perspective view of the face contact member which may be employed in conjunction with my device;

Fig. 4 is a sectional view taken substantially on the line 4—4 of Fig. 2;

Fig. 5 is a sectional view taken substantially on the line 5—5 of Fig. 2;

Fig. 6 is a sectional view taken substantially on the line 6—6 of Fig. 1;

Fig. 7 is a sectional view taken substantially on the line 7—7 of Fig. 2;

Fig. 8 is a detail view in section of a modified form of exhaust valve and respirator parts for attaching the valve to the respirator; and

Fig. 9 is a sectional view taken substantially on the line 9—9 of Fig. 8.

Referring now to Figs. 1 and 2, the preferred form of my device comprises a unitary wedge-shaped main body 10 having oppositely inclined 55 and converging side faces 11 and 12 which are

joined together by similarly formed upper and lower faces 13. The entire body portion 10 including side faces 11 and 12 and upper and lower faces 13 is preferably moulded into one piece of flexible and resilient rubber so that the side walls 5 may fold against each other when not in use in order to occupy a minimum amount of space and be adapted to be carried in a pocket. Upper and lower faces 13 are provided with identical cut-outs 14. The function of cut-outs 14 is to permit the entrance of and fit tightly around the bridge of the user's nose. Since the cut-outs are identical the device may be rotated through substantially one hundred eighty degrees and yet fit the wearer's face efficiently in one position as 15 well as the other.

Forwardly inclined lugs 15 are arranged on upper and lower faces 13 for the purpose of anchoring face contact member 16 which is shown in Fig. 3 before attachment to the respirator. 20 Face contact member 16 is generally frustoconical in shape and knitted into a continuous elongated band. Attaching loops 17 are provided at points one hundred eighty degrees apart, adjacent the larger end of member 16. The member 25 16 may then be attached to the respirator by inserting the smaller end into the open or rear end of the respirator and turning the larger end outwardly and over the rear edges of side faces 11 and 12 and upper and lower faces 13. When this 30 operation is completed so that the member 16 covers entirely said rear edges the attaching loops 17 may be hooked onto the forwardly inclined securing lugs 15.

Supporting straps 18 and 19 may be secured 35 to opposite side faces 11 and 12 respectively at points adjacent but forwardly of the rear edges of said side faces. Attaching bolts 20 may be used for this purpose and because of the positioning of said bolts they do not interfere with the 40 outward and forward folding of face contact member 16 to any detrimental extent. A securing buckle 21 is carried by strap 18 and cooperates with the free end of strap 19. Straps 18 and 19 are of course of sufficient length to extend around 45 the head of the user so as to attach the respirator securely in place for filtering the inhaled air.

Oppositely inclined side faces 11 and 12 are provided with inhaling apertures 22 and 23. Preferably these apertures are of large size and arranged in a circular formation with one aperture serving as the imaginary axis of the circular formation. Extending entirely around the groups of apertures 22 and 23 are outwardly extending 55

annular flanges 24 and 25 respectively, and a plurality of transversely extending attaching bosses 26 and 27 protrude at spaced points from the outer faces of flanges 24 and 25 respectively. Preferably the flanges 24 and 25 are formed integrally with the side faces 11 and 12 respectively and of the same character of material. However, the flanges 24 and 25 may be made of greater thickness than the side faces so as to make them relatively more stiff and less subject to deformation. Filtering material 28 is arranged over apertures 22 and 23 and within the flanges 24 and 25. Screens 29 may be placed over the outer ends of said flanges so as to hold filtering material 28 in place. Caps 30 having enlarged annular openings 31 may be placed over screens 29 and flanges 24 and 25 and attached to said flanges by the entrance of attaching bosses or lugs 26 and 27 into the slots 32 which are carried in the cylindrical faces of caps 30. Caps 30 are preferably attached by compressing flanges 24 and 25 so that the attaching lugs 26 and 27 may be brought within the cylindrical walls of caps 30 and when the lugs 26 and 27 are in alignment with slots 32 the resilience of the flange material causes the attaching lugs to be projected outwardly and through the slots 32. The caps may be removed by pressing the lugs inwardly and through slots 32.

30 The faces 11 and 12 and upper and lower faces 13 extend forwardly and into a wall forming a bulbous extension 33. The bulbous extension 33 is preferably longer from top to bottom than from side to side so as to offer very slight obstruction to the vision of the user. Annular openings 34 are provided at the top and bottom of bulbous extension 33 for the purpose of permitting the exit of exhaled air and so placed as to permit drainage of water of condensation from the interior bulbous chamber. Referring now to Figs. 6 and 7, the interior wall of the bulbous extension 33 is thickened so as to provide an abutting and retaining bead 35 whose function is to serve as an abutment against which the exhaust valve 45 carrying frame 36 is adapted to be held. Retaining lugs 37 are spaced forwardly of bead 35 on the interior wall of bulbous extension 33 and are preferably arranged on opposite walls of said extension. The bead 35 and lugs 37 thus in effect 50 provide a retaining groove in which the exhaust valve frame 36 is constrictively held because the space between the forward edge of bead 35 and the rearward edge of lugs 37 is somewhat less than the width of flange 38 of exhaust valve frame 55 36.

Referring now to Figs. 4 and 5, the exhaust valve frame 36 heretofore mentioned comprises a somewhat ovally shaped base plate 39 and the forwardly extending flange 38 heretofore mentioned. Spaced exhaust openings 40 are placed adjacent opposite ends of plate 39 and because of the positioning of valve frame 36 are adjacent the upper and lower walls of bulbous extension 33. Consequently they are near annular openings 34 65 and moisture of condensation may find exit from the interior of the respirator through openings 40 and openings 34. These openings function in identically the same manner regardless of whether the respirator is used in the position in which it is 70 shown in Fig. 2 or whether it is rotated through one hundred eighty degrees. The outer perimeter of flange 38 is somewhat greater than the inner perimeter of the wall of bulbous extension 33 which lies between lug 37 and bead 35. Consequently the flange is constrictively retained at

this point and an air-tight connection results. An exhaust valve disc or flap is secured to the forward face of base plate 39 by a pair of spaced pins 42. The disc or flap 41 is preferably made from a thin sheet of extremely flexible and resilient rubber material and is of sufficient size to cover, entirely, openings 40. The pins 42 are preferably placed intermediate the openings 40 and act as a hinge upon which opposite ends of flap 41 virtually pivot when air is exhaled from the respirator. Because of the flexibility and resilience of the flap 41 the opposite ends thereof immediately return to lie flat upon the forward face of base plate 39 when pressure within the respirator is reduced to that existing outside the 10 respirator. As soon as inhalation starts the flap 41 is drawn tightly against the plate 39 because of the inward suction or pressure. The pins 42 are spaced apart so as to prevent the rotation of flap 41 since rotation might cause the outer edges of the flap to drag on the inner wall of flange 38 and prevent efficient operation of the flap. However, a pin having a square shank or transversely protruding lugs might be employed instead of the two spaced pins. 15

A modified form of exhaust valve is shown in Figs. 8 and 9 and would be adaptable for use with a respirator having a bulbous extension which is circular in cross-section so that the bead 43 and spaced lugs 44 would provide an annular groove 30 for the retention of annular exhaust valve frame 45. The base plate 46 in such a construction would of course be circular as would the flange 47. Exhaust openings 48 might then be arranged around the attaching pin 49 as an axis and the 35 flap or disc 50 could be held in place by pin 49 and rotate freely on said pin without danger of dragging upon the inner wall of flange 47. I prefer the form illustrated in Figs. 1, et cetera, to the form shown in Figs. 8 and 9 because there 40 is less obstruction to the vision when those forms of exhaust valves and bulbous extensions are used. 45

The removal of the exhaust valve frames from the bulbous extensions is a relatively simple 50 operation and may preferably be carried out by deforming the bulbous extension until one of the retaining lugs 37 (or 44 in the modified form) is displaced so that one side of the exhaust valve frame may be pushed forwardly. The entire valve 55 frame may then be withdrawn from the rear of the respirator by turning said frame upon its edge. The valve frame may be reinserted by pushing it into the bulbous extension edgewise, pressing one side of the frame into the retaining groove, and then deforming the wall of the bulbous extension sufficiently to permit the other side of the valve frame to be forced into the retaining groove. 60

From the foregoing description it can be seen that I have accomplished my objects in an extremely economical manner and provided a device which may be used for the intended purpose of filtering inhaled air without any great discomfort to the user. The latter feature is 65 aided by the use of two incoming filter chambers of large area and the use of a quick acting and easily operated exhaust valve. The placing of the exhaust valve immediately forwardly of the nostrils and mouth of the user aids considerably in permitting the user to breathe lightly and freely and yet be protected from the dangerous effects of noxious gases and foreign particles. 70

While I have illustrated and described the pre- 75

ferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. A respirator comprising a forwardly tapered main body portion formed of flexible material and a bulbous chamber formed integrally therewith at its forward end, there being a constricted passageway formed between the body portion and said chamber, the flexible walls of the bulbous chamber adjacent said passage being formed to provide a valve frame seat, a valve frame and valve, and means for retaining said valve frame on said seat, said valve frame and valve being removable by flexing the walls of the chamber and passing the valve frame and valve through said constricted passageway, substantially as described.

2. A respirator comprising a pair of forwardly tapered flexible side walls connected at their longitudinal edges forming a larger open rear end for engaging over the breathing openings of the face and a smaller forward end, the forward end being expanded into a vertically elongated bulbous chamber arranged with its major axis vertical and having an exhaust opening at each end thereof, there being a constricted passageway between said chamber and the remaining portion of the device, and a one-way valve de-

tachably mounted in said chamber and adapted to be removed through said constricted passageway, substantially as described.

3. A respirator comprising a main body portion formed of a pair of forwardly tapered flexible side walls connected at their longitudinal edges and adapted to fold against each other, and said body portion being expanded forwardly at the ends of the side walls to form a vertically elongated bulbous chamber, said chamber being closed at the front and having an exhaust opening at both upper and lower ends, and a one-way valve mounted in said chamber, in which respirator the bulbous chamber is provided with an inwardly opening annular seat adjacent the constricted opening and a rigid exhaust valve frame removably held in said seat and a valve carried by said frame, substantially as described.

4. A respirator comprising a body portion constructed of a pair of forwardly tapered flexible side walls connected at their longitudinal edges forming a larger open rear end for engaging over the breathing openings of the face and a smaller forward end, the upper and lower portions of the face engaging edge being symmetrical, and the forward end terminating in an integral bulbous chamber closed at the front and having similar openings at the upper and lower ends thereof, each constituting both an exhaust and a drain port, and an exhaust valve and rigid valve frame mounted in said bulbous chamber and removable through said body portion, substantially as described.

HARVEY S. COVER.
